(57) **CLAIM**

The ornamental design for an intraoral camera, as shown and described.

DESCRIPTION

FIG. 1 is a perspective view of the intraoral camera, showing my new design;

FIG. 2 is a front plan view thereof;

FIG. 3 is a back plan view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines depict environmental subject matter only for illustrative purposes and form no part of the claimed design.
